UNITED STATES PATENT OFFICE.

ORVILLE B. JOHNSON, OF BOSTON, MASSACHUSETTS.

ELECTRICAL RAILWAY-SIGNAL.

SPECIFICATION forming part of Letters Patent No. 248,326, dated October 18, 1881.

Application filed May 20, 1881. (No model.)

To all whom it may concern:

Be it known that I, ORVILLE B. JOHNSON, of Boston, in the county of Suffolk and State of Massachusetts, have invented certain Improvements in Electrical Railway-Signals, of which the following is a specification.

This invention relates to that class of electric railroad-signals in which an alarm is sounded at a crossing or other given point by the action 10 of an approaching train of cars on a magneto-generator or other suitable electric device.

Heretofore, so far as I am aware, in this class of signals the signal has generally either been operated only while the train of cars is passing 15 the point where the magneto-generator or other electric device is located, so that there is no operation of the signal during the interim while the train is passing from said point to the point where the signal is located or has 20 been operated for a fixed length of time, regardless of the length of time occupied by the train in passing from one point to the other, so that there is liability of the signal being operated after or stopping before the train has passed.

25 My invention has for its object to provide an improved signal mechanism adapted to be continuously operated during the passage of the train from the point where the electric device is located to the signal itself, and to be 30 stopped by the action of the train when the latter reaches the point where the signal is located; and to this end the invention consists in the improvements which I will now proceed to describe and claim.

35 Of the accompanying drawings, forming part of this specification, Figure 1 represents a side elevation of a signal mechanism embodying my invention, one of the sides of the supporting-frame being removed to show the mechanism more clearly. Fig. 2 represents a front elevation of the same. Fig. 3 represents a top view. Figs. 4 and 5 represent side elevations 40 of parts of the mechanisms, showing their positions during different parts of the operation. Figs. 6 and 7 represent, respectively, sections 45 on lines $y-y$ and $x-x$, Figs. 4 and 5, and Fig. 8 represents a side elevation of a part detached.

The same letters of reference relate to the same parts in all the figures.

50 In carrying out my invention I provide a supporting-frame, a , a bell or gong, b , striking mechanism therefor, a motor for said striking

mechanism, adapted to be set for action by the wheels of a passing train of cars, a locking device adapted to be operated simultaneously 55 with the setting of the motor to prevent the latter from operating the striking mechanism, and an electro-magnet, A , adapted to be operated by the action of a subsequently approaching train at a distant point, to release the locking mechanism and permit the striking mechanism to be operated by its motor while the train is advancing from said distant point to the signal.

In the drawings I have shown the above- 65 named elements embodied in the best practical form which I have devised up to the present time.

The striking mechanism consists of a train 70 of gearing, $c d e f$, an escapement, g , preferably an ordinary anchor-escapement, a pendulum, h , on the arbor h' , carrying the anchor of the escapement, and a bell-hammer, i , pivoted at j and arranged to be operated to strike the bell by pins k on one of the wheels of the train 75 of gearing.

The motor of the striking mechanism is composed of a lever, l , pivoted upon the arbor of the gear c , and carrying a dog, m , engaging with a ratchet, n , rigidly attached to said arbor, and a spring, p , attached at one end to the lever l , and at the opposite end to a fixed 80 object, and adapted, when properly set for action, to move the lever l in the direction indicated by the arrow in Fig. 1.

85 The mechanism for setting the spring for action consists of a lever, o , arranged to be depressed by the wheels of a passing train of cars, as shown in dotted lines in Fig. 1, either directly or through suitable intermediate mechanism, and a rod, l' , connecting the levers l and o , so that when the latter is depressed, as shown, the lever l will be turned on its pivot in the proper direction to set the spring for action.

I do not limit myself to the use of a spring 95 as a motor, however, as a weight may be arranged to be raised or set for action on the striking mechanism without departure from the spirit of my invention.

The locking mechanism is composed of an 100 arm, q , rigidly attached to the arbor h' ; a dog, r , pivoted to the arm q , and having its downward movement on its pivot limited by any suitable means, preferably by a horizon-

tal bar or track, *s*, adapted to support the end of the dog, as hereinafter described; a lever, *t*, pivoted at *u*, and provided with a shoulder, *v*, (see Fig. 8,) adapted to be raised above the upper edge of the bar *s* or to be depressed below the same; a detent, *w*, on the armature-lever of the electro-magnet *A*, held normally by a retracting-spring in position to hold the lever *t* in an elevated position when the magnet *A* is not excited, and devices operated by a passing train of cars to raise the lever *t*, the last-named devices consisting, preferably, of a notched disk or cam, *B*, on an arbor, *C*, journaled in the frame *a*, an arm, *D*, on the arbor *C*, and a rod, *E*, connecting the arm *D* to the connecting-rod *l*. When the lever *t* is raised so that its shoulder *v* projects above the bar *s*, and the electro-magnet *A* is not excited, said lever is held in said position by the detent *w*, and the shoulder *v* is in position to engage the dog *r* and prevent the arm *q* from vibrating, thus locking the escapement and preventing the striking mechanism from being operated by its motor. When the lever *t* is lowered below the limit of the downward movement of the dog *r* the latter is disengaged from the shoulder *v*, and is free to reciprocate on the smooth upper edge of the bar *s*. The arm *q* is therefore free to vibrate, and the striking mechanism is released, so that it will be operated by the motor.

The upward movement of the lever *t* is effected by the depression of the lever *o*, which partially rotates the cam *B* and causes the edge of the latter to bear on a pin, *p'*, on the side of the lever *t* and raise the lever to the position shown in Fig. 1, the arm or detent *w* springing back under the lever *t* and holding it up. As soon as the lever *t* is raised a spring, *H*, raises the lever *o*, and, through the rods *l* and *E* and arm *D*, rotates the cam *B* until its notch comes under the pin *p'*, so that the lever *t* can drop below the upper edge of the bar *s* when the detent *w* is withdrawn from under said lever.

The operation of the described mechanism as a whole is as follows: Suppose the motor of the striking mechanism to be set for action and the locking devices adjusted to prevent the operation of the striking mechanism. The wheels of an approaching train of cars act on a magneto-generator or a circuit-closer or other suitable device in electric connection with the electro-magnet *A*, and at a suitable distance from the signal, and excite said magnet, causing its armature to withdraw the detent *w* from under the lever *t*, thus releasing said lever and suffering it to drop, as shown in Fig. 4. The striking mechanism is thus allowed to operate the pendulum and escapement, regulating the

speed of operation and causing the hammer to strike the bell at a moderate rate until the train reaches the point where the signal is located. When the wheels of the train act on the lever *o* the lever *t* is moved to the position shown in dotted lines in Fig. 1, thereby setting the spring *p* for action. At the same time the cam *B* is rotated and the lever *t* raised to arrest the dog *r* and lock the striking mechanism, so that when the train of cars passes on it leaves the striking mechanism ready for operation, but locked, so that it will not operate until the succeeding train acts on the electrical devices to excite the electro-magnet *A*. The operation of the signal is therefore insured during and limited to the time in which the train is passing from the electrical devices to the signal.

Having thus described my invention, I claim—

1. An automatic signaling apparatus for railroad-crossings, consisting of the following elements, namely: a gong-sounding mechanism controlled by an escapement, a pivoted dog operated by the escapement, a toothed bar normally engaged with the dog to hold the gong-sounding mechanism in check, a smooth supporting-bar, *s*, to allow the dog to reciprocate, a detent for holding the toothed bar normally in engagement with the dog, an electro-magnet for shifting the detent so as to release the toothed bar from the dog and set off the gong-sounding mechanism, and devices operated by the wheels of a passing train for re-engaging the toothed bar with the dog, to again arrest the gong-sounding mechanism, substantially as described.

2. The combination of the signal-operating mechanism having the arm *q* on one of its arbors, the motor, the releasing-magnet, and the locking mechanism, composed of, first, a dog pivoted to the arm *q* and having a limited downward movement; second, a pivoted shouldered lever arranged to be raised and lowered, and thereby arrest and release the dog; third, devices, substantially as described, adapted to be operated by the wheels of the train of cars to raise the lever; and, fourth, a stop or detent on the armature of the releasing-magnet, adapted to hold the lever in its raised position, as set forth.

In testimony whereof I have signed my name to this specification, in the presence of two subscribing witnesses, this 17th day of May, A.D. 1881.

ORVILLE B. JOHNSON.
